THREE-SIDE LOCK SNAP FASTENER

Harold S. van Buren, Jr., Cambridge, Mass., assignor to United-Carr Fastener Corporation, Cambridge, Mass., a corporation of Massachusetts

Application December 30, 1948, Serial No. 68,153

10 Claims. (Cl. 24—218)

1

This invention relates to a three side lock snap fastener assembly, and has particular reference to a socket for such a fastener which may be readily applied to a supporting sheet by an automatic machine.

Three-side lock snap fasteners are extensively used in installations where it is essential or desirable that the fastener become disengaged by a separating force applied on one predetermined side only. Since the sockets of such fasteners must be applied to the supporting sheet with the unlocking side in a predetermined direction in relation to the supporting sheet, it has heretofore been impossible to apply such sockets by means of automatic machines. Instead, the sockets must be applied manually, and each socket positioned individually with the unlocking side in correct relation to the supporting sheet. Such an operation is relatively expensive and time consuming, and the sockets are frequently incorrectly applied.

The object of this invention is to provide an improved three-side lock snap fastener assembly comprising a socket member and a cooperating stud, in which the socket member has means thereon to enable it to be properly positioned by an automatic machine so that it may be applied to a supporting sheet with the unlocking side of the socket in a predetermined direction in relation to the supporting sheet.

A further object of the invention is to provide a three side lock snap fastener socket member for use with a stud of the type which has an enlarged portion thereon, in which the socket member has spring means disposed therein to engage the stud on one side and to force the stud into engagement with the socket on the other side.

Other objects of the invention will, in part, be obvious, and will, in part, appear hereinafter.

For a fuller understanding of the nature and objects of the invention, reference should be had to the following detailed description, taken in conjunction with the accompanying drawing, in which:

Fig. 1 is a plan view of a socket member and an associated supporting sheet;

Fig. 2 is a plan view of the underneath side of the socket member of Fig. 1;

Fig. 3 is a view in elevation, partly in section of the socket member and an assembled stud member taken on line 3—3 of Fig. 1;

Fig. 4 is a view in perspective of a spring member utilized in the socket member of Fig. 3;

Fig. 5 is a plan view, partly in section, of the

socket member, showing the relationship between the spring and an assembled stud member;

Fig. 6 is a view in elevation, partly in section, of the socket illustrating the method of assembling the stud therein;

Fig. 7 is a view taken on line 7—7 of Fig. 3 showing in detail the relationship between the spring member and the socket member.

Referring to the drawing, the preferred embodiment of the improved fastener comprises a socket member 10 having a body portion 12 formed of a base plate 14 and a circular wall 16 attached thereto by an attaching rim 18. A rivet 20 is disposed in the base plate 14 for attaching the socket to a supporting sheet 22 and an attaching cap 23. The base plate 14 is provided with a number of tines 21 which are adapted to dig into the supporting sheet 22 and thereby prevent rotation of the socket member on the supporting sheet. Similar tines (not shown) may be provided on the attaching cap 23 to prevent rotation thereof on the supporting material. The circular wall 16 is turned inwardly at its lower end to form a lip 24 and an opening 26 for receiving the stud member 28. The lip 24 has a slot 25 for receiving an engaging portion 27 of a spring member 30 which is disposed in the socket. In the preferred form, the spring member 30 comprises a split ring having a loop therein to form the engaging portion 27 for engaging the stud member 28, and a projection 31 extending from the loop to behind the lip 24, the engaging portion and the projection operating in a manner which will be herein-after described.

The stud member 28 comprises a shank 32 having means thereon for attaching to a supporting sheet 33, and an enlarged portion 36 on the shank which forms a flat shoulder 38 for engagement with the lip 24 when the stud is in assembled position in the socket.

To assemble the stud and socket, the stud member 28 is snapped into the socket 10 in the conventional manner, whereby the spring member 30 engages one side of the stud behind the shoulder 38, retaining the stud in the socket on that side, and exerting a lateral force on the stud to bias it against the lip 24 of the opening on the opposing side, thereby insuring that the shoulder 38 is retained in engagement behind the edge of the lip 24.

It will be readily seen that although the stud may be easily disengaged from the socket by a separating force applied on the side of the assembly on which the engaging portion of the spring member 30 is located, a separating pull applied at any other

point on the periphery cannot effect the separation of the members, since in this case the flat shoulder of the stud engages the lip 24 and thereby prevents the stud from coming out of the socket.

In disengaging the stud from the socket by a separating force applied on the proper side of the assembly, the engaging portion of the spring may tend to pull out of the socket through the slot 25. In the preferred embodiment of the invention, this is prevented by the projection 31, which extends from the engaging portion 27 to behind the lip 24, and engages the lip 24 when the stud is removed from the socket.

In the illustrated device, the engaging portion 27 of the spring member extends slightly above the body 12 of the socket member thereby providing means by which the socket may be aligned by positioning means of an automatic machine to enable the socket to be applied to a supporting sheet with the engaging means of the spring in a predetermined direction in relation to the supporting sheet. In such automatic machines, the sockets to be applied to a sheet are transferred from a supply drum to the attaching mechanism by any suitable transforming mechanism. During transfer the sockets may be aligned by the positioning means into a predetermined position in relation to the attaching mechanism and the supporting sheet.

Many modifications of the device are possible within the scope of the invention. In some applications it may be desirable to bend the lip 24 downwardly into the socket, to provide an inclined or rounded portion adjacent the opening to facilitate insertion of the stud into the socket. Although in the illustrated device the means on the socket for cooperating with the directing fingers of an automatic machine is the portion of the spring extending above the socket, other means may be used, such as a small projection from the body itself, extending sufficiently far from the body to engage the directing fingers. The outer periphery of the body may be of any convenient shape. Although the device is readily adapted for use in automatic attaching machines, it can also be attached manually if desired.

Since certain other changes may be made in the device without departing from the scope of the invention, it is intended that the above description should be interpreted in an illustrative rather than in a limiting sense.

I claim:

1. A snap fastener socket for use with a stud of the type having an enlarged portion thereon, the socket comprising a body adapted to be secured to a supporting material, the body having an opening on one face thereof to receive the stud and a recess adjacent the opening to receive the enlarged portion of the stud, and spring means extending from said opening beyond said one face and disposed to engage the stud on one side and bias it into engagement with an edge of the opening on the opposing side.

2. A snap fastener socket for use with a stud of the type having an enlarged portion thereon, the socket comprising a body adapted to be secured to a supporting material, the body having an opening therein to receive the stud and a recess adjacent the opening to receive the enlarged portion of the stud, and spring means disposed to engage the stud on one side and bias it into engagement with an edge of the opening on the opposing side, the spring means extending beyond the body for cooperation with position-

ing means of an automatic machine to enable the socket to be applied to a supporting sheet with the spring means in a predetermined direction in relation to the supporting sheet.

3. A snap fastener socket for use with a stud of the type having a shank and an enlarged portion on the shank forming a flat shoulder which is substantially perpendicular to the axis of the neck, the socket comprising a hollow body adapted to be secured to a supporting sheet, the body having an opening on one face thereof to receive the stud, and a recess adjacent the opening to receive the enlarged portion of the stud, a wall of the recess having a flat portion substantially perpendicular to the axis of the opening and disposed to engage the flat portion of the stud shoulder when the stud is in the assembled position in the socket, and spring means in the socket extending through said opening beyond said one face and adapted to engage the stud shoulder on one side of the stud and bias the stud laterally whereby the flat portion of the stud shoulder on the opposing side is maintained in engagement behind the flat portion of the wall of the recess on the opposing side.

4. A snap fastener socket for use with a stud of the type having a shank and an enlarged portion on the shank forming a flat shoulder which is substantially perpendicular to the axis of the neck, the socket comprising a hollow body adapted to be secured to a supporting sheet, the body having an opening therein to receive the stud, and a recess adjacent the opening to receive the enlarged portion of the stud, a wall of the recess having a flat portion substantially perpendicular to the axis of the opening and disposed to engage the flat portion of the stud shoulder when the stud is in the assembled position in the socket, spring means in the socket adapted to engage the stud shoulder on one side of the stud and bias the stud laterally whereby the flat portion of the stud shoulder on the opposing side is maintained in engagement behind the flat portion of the wall of the recess on the opposing side, the spring means extending beyond the body of the socket for cooperation with positioning means of an automatic machine whereby the socket may be aligned in a predetermined direction by the machine for application to a supporting sheet.

5. A three side lock snap fastener socket for use with a stud having a shank and an enlarged portion on the shank forming a flat shoulder which is substantially perpendicular to the axis of the shank, the socket comprising a base member adapted on the lower portion for attaching to a supporting sheet, a circular wall on the upper portion of the base member, the wall being turned inwardly at its upper portion to form a lip which defines an opening to receive a stud member, and a split ring spring member disposed in the socket having an engaging portion extending through said opening beyond said wall and disposed to engage the stud behind the shoulder on one side and bias the stud into engagement with the lip on the opposing side.

6. A three side lock snap fastener socket for use with a stud having a shank and an enlarged portion on the shank forming a flat shoulder which is substantially perpendicular to the axis of the shank, the socket comprising a base member adapted on the lower portion for attaching to a supporting sheet, a circular wall on the upper portion of the base member, the wall being turned inwardly at its upper portion to form a

lip which defines an opening to receive a stud member, and a split ring spring member disposed in the socket having an engaging portion disposed to engage the stud behind the shoulder on one side and bias the stud into engagement with the lip on the opposing side, a portion of the split ring spring member extending above the body of the socket for engagement with positioning means of an automatic attaching machine to enable the machine to align the socket whereby the engaging portion of the spring member is in a predetermined direction in relation to a supporting sheet to which it is to be attached.

7. A three side lock snap fastener socket for use with a stud having a shank and an enlarged portion on the shank forming a flat shoulder which is substantially perpendicular to the axis of the shank, the socket comprising a base member adapted on the lower portion for attaching to a supporting sheet, a circumferential wall on the upper portion of the base member, the wall having inwardly turned lips at its upper portion to outline an opening to receive the stud member, the lips having a slot in one portion thereof, a split ring spring member disposed in the socket having an engaging portion disposed in the slot to engage one side of the stud behind the stud shoulder when the stud is in assembled position in the socket, and to bias the stud laterally into engagement with the lip on the opposing side whereby the stud shoulder is retained in engagement behind the lip on the opposing side, the engaging portion of the spring member extending through the slot and above the body of the socket to provide means for cooperation with positioning means of an automatic attaching machine, and means on the engaging portion of the spring member to prevent the engaging portion from being pulled through the socket when the stud is removed therefrom.

8. A three side lock snap fastener assembly, comprising a stud and a cooperating socket, the stud having a shank, an enlarged portion on the shank forming a flat shoulder substantially perpendicular to the axis of the shank, the socket comprising a base member adapted on the lower portion for attaching to a supporting sheet, a circular wall on the upper portion of the base member, the wall being turned inwardly at its upper portion to form a lip which defines an opening to receive a stud member, and a split ring spring member disposed in the socket having an engaging portion extending through said opening beyond said wall and disposed to engage the stud behind the shoulder on one side and bias the stud into engagement with the lip on the opposing side.

9. A three side lock snap fastener assembly, comprising a stud and a cooperating socket, the

stud having a shank, an enlarged portion on the shank forming a flat shoulder substantially perpendicular to the axis of the shank, the socket comprising a base member adapted on the lower portion for attaching to a supporting sheet, a circular wall on the upper portion of the base member, the wall being turned inwardly at its upper portion to form a lip which defines an opening to receive a stud member, and a split ring spring member disposed in the socket having an engaging portion disposed to engage the stud behind the shoulder on one side and bias the stud into engagement with the lip on the opposing side, a portion of the split ring spring member extending above the body of the socket for engagement with positioning means of an automatic attaching machine to enable the machine to align the socket whereby the engaging portion of the spring member is in a predetermined direction in relation to a supporting sheet to which it is to be attached.

10. A three side lock snap fastener assembly comprising a stud adapted to be secured to a supporting sheet, the stud comprising a shank, an enlarged portion on the shank forming a flat shoulder which is substantially perpendicular to the axis of the shank, the socket comprising a base member adapted on the lower portion for attaching to a supporting sheet, a circumferential wall on the upper portion of the base member, the wall having inwardly turned lips at its upper portion to outline an opening to receive the stud member, the lips having a slot in one portion thereof, a split ring spring member disposed in the socket having an engaging portion disposed in the slot to engage one side of the stud behind the stud shoulder when the stud is in assembled position in the socket, and to bias the stud laterally into engagement with the lip on the opposing side whereby the stud shoulder is retained in engagement behind the lip on the opposing side, the engaging portion of the spring member extending through the slot and above the body of the socket to provide means for cooperation with positioning means of an automatic attaching machine, and means on the engaging portion of the spring member to prevent the engaging portion from being pulled through the socket when the stud is removed therefrom.
